GAS-TIGHT PACKING BOX

Harvey G. Kittredge, Dayton, and Sylvester J. Broderick, Yellow Springs, Ohio, assignors to Foilfilm, Inc., Dayton, Ohio, a corporation of Ohio

Application August 19, 1935, Serial No. 36,758

8 Claims. (Cl. 229—14)

This invention relates to gas-tight containers. It is the object to provide containers that are impervious to moisture, the entrance of gases, and which will be heat and light reflecting and impervious to the entrance of bacteria, vermin, and the like.

Likewise, it is an object to similarly prevent the exit of gas, moisture, etc., from the interior of the container thus formed.

10 It is an object to provide such a container that is light in weight, that is extremely cheap to manufacture, that can be produced in quantity, that can be manufactured in flat condition and shipped in flat condition and assembled by the 15 user, and which can be sealed by the user in a simple manner without tools or special machinery.

It is our object to eliminate the necessity for fusing and welding to form a gas-tight container.

20 It is our object to provide such container in the form of a sack, box, bottle, or any of the standard forms.

It is our particular object to be able to make the container out of such extremely cheap materials as paper, pasteboard and boxboard, and 25 to so seal the container that when it is desired to open it it can be opened by disrupting the seal but without completely destroying the container, so that it may still serve as a support for the contents until the contents are used.

30 It is an object to provide a folding or collapsible container such as the ordinary box blank or bag blank, to apply thereto permanently by an impervious adhesive coating a structurally weak metal film such as metal foil arranged in thickness from .00025 to .001. This foil is applied permanently to what will become the interior of the box, although it can likewise be applied to the exterior, if it is not desired that the contents of the box engage the foil. Standing by itself the foil is too delicate and lacks structural strength to be formed as a container. It is our object to thus line the blank of a folding box leaving portions of the box not engaged by the foil, so that the box can be folded with a continuous inner sheet of foil that extends throughout the bottom and side walls as a continuous sheet and beneath the top and along the top flap.

40 It is an object to provide a portion of the box side walls with laterally-extending turned-over ledges to form upper sealing surfaces for engagement by the box cover, which is either hinged to the box or is slidably mounted thereover.

45 It is an object to provide a sealing medium for sealing the engaging surfaces of the top and the side walls of the box to form a gas-tight container. The resulting product is a foil-lined box that is completely sealed.

50 It is an object to provide material that will

cause the metal to adhere to it and to the container and to provide material that can be applied at room temperature in any desired manner to the engaging surfaces of the top and bottom of the box to form a seal that will be strong, 5 yielding and impervious to the entrance or exit of gas, moisture, etc., thus enabling the ordinary user to assemble a flat box or other container and to seal it by squeezing the material from a tube, applying with a brush, a roller or the like. 10 It is an object to provide such a material that will withstand the expansion and contraction to which it will be subjected.

15 It is a further object to provide a strong sealing adhesive which can be applied hot and which upon cooling will strongly adhere to either the box or the metal or both.

Referring to the drawings:

Figure 1 is a perspective of a container with the bottom and side walls in section and the top 20 thereof in section, showing a type where the seal between the box cover and the box side walls is on the outside of the upper edge of the box walls.

Figure 2 is a section on line 2—2 of Figure 1.

Figure 3 is a similar view to Figure 1, showing 20 a type with an inwardly-turned ledge on the box.

Figure 4 is a section on the line 4—4 of Figure 3.

Figure 5 is a plan view of a folding box blank before the application of the foil thereto.

25 Figure 6 is a perspective of the closed folded box.

Figure 7 is a perspective of a box opened with the foil strips not yet folded back over the paper ledges for sealing purposes. This type of box is 30 one in which the foil is applied after the box is assembled, there being one strip of foil running in one direction, and another strip of foil running in another direction, the edges thereof overlapping and sealed to one another.

35 Figure 8 is a section on the line 8—8 through a corner of the box shown in Figure 7.

Figure 9 is a section on the line 9—9 through a side wall of the box.

Figure 10 is a section on the line 10—10 of 40 Figure 7.

Figure 11 is a section on the line 11—11 of Figure 7.

Figure 12 is a perspective of a paper sack having applied thereto an inner sack of foil which 45 has been permanently anchored thereto.

Figure 13 is a section through the mouth of the bag after it has been turned over and the sealing medium applied thereto.

50 Figure 14 is a section through the mouth of the bag after the sealing medium has been turned over by further folding of the mouth of the bag for final sealing of the bag.

Figure 15 is a top plan view of a folding box 55

blank with the foil applied thereto on the inside thereof.

Figure 16 is a plan view of the outside of the box blank after the foil has been applied to the inside and partially on the outside.

Figure 17 is a perspective of the box that has now been folded with the continuous sheet of the foil therein, but with the top not yet sealed.

Figure 18 is a section on the line 18-18 through the sealed box, the section being taken transversely of the box, shown in Figure 17.

Figure 19 is a section on the line 19-19 of Figure 17.

Figure 20 is a section on the line 20-20 through the corner of the box shown in Figure 17.

Figure 21 is a section on the line 21-21 of Figure 15.

Figure 22 is a section on the line 22-22 of Figure 15.

Referring to the drawings in detail, we prefer to use aluminum foil, but any desired metallic foil may be employed that comprises a very thin, structurally weak metallic foil that is impervious. This foil is preferably applied as follows: One side of the foil is coated with 20 grams of vinyl acetate, 2.5 grams of tricresyl phosphate, and 20 cc. of toluol. This material is applied to metal at room temperature and preferably permitted to dry until tacky in a current of air at about 212° F. for about five minutes. These temperatures and times will depend upon the amount of solvent used, the speed of the air current, etc.

While the foil has one side of the adhesive tacky the paper and foil are pressed together. If desired the adhesive material can be applied on the paper or pasteboard of the box or container. The foil then can be applied to the adhesive surface of the paper or pasteboard by the application of pressure. The adhesive can be applied to either the foil or the paper or pasteboard by spreading, spraying, by rolls or the like.

It is to be understood that one of the primary problems has been the development of an adhesive that is impervious to moisture, that is not moisture-absorbent, that is markedly adhesive, that will not penetrate and stain the pasteboard or paper, and that is very adherent to materials that are extremely hard and smooth, such as aluminum foil.

After the container has been thus made it is necessary to seal the metal-to-metal or metal and pasteboard or paper surfaces with a sealing medium that is sufficiently strong and resilient to be satisfactory, that is gas-tight, and that can be applied at ordinary room temperatures and will adhere with very slight pressure, in view of the fact that in many forms of containers it will not be possible to apply a material amount of pressure in sealing. Where the first-mentioned type of adhesive material cannot be employed, then the following sealing compound has been found satisfactory. We employ 25% of a viscous adhesive chlorinated diphenyl, 50% of a solid chlorinated diphenyl and 25% of paracoumarone resin. These several materials are mixed together at 100° C. and thoroughly stirred and applied hot by a brush or other means. The viscosity of the sealing compound is controlled by controlling the temperature.

This adhesive is the subject of a co-pending application of Harvey G. Kittredge and Sylvester J. Broderick, Serial No. 37,210, filed August 21, 1935, which has now matured into Letters Patent No. 2,096,110, dated October 19, 1937, and the subject matter thereof is reserved for said

application. The material used for applying the foil is the subject of an application of Harvey G. Kittredge and Sylvester J. Broderick, Ser. No. 7070, of February 18, 1935, and the subject matter thereof is reserved to be covered thereby. 5

Referring to the drawings in detail, and particularly the box shown in Fig. 1, 1 designates the bottom and 2 the side walls of a box. 3 designates the attaching material for the foil sheet 4. It is preferred that the foil and adhesive be carried over the top of the side walls 2 to form a ledge of foil as at 4, and then carry the adhesive and foil over the outside of the upper edge of the box as at 5 and 6. Upon the outside of the foil 5 is applied, when the box is to be sealed, 15 the sealing medium 7 heretofore described. While this is still hot and plastic or viscous, the cover, having a top 8 and side walls 9 is applied, and slight pressure applied to the cover over the area 7. If desired, the sealing medium 7 may be carried on top of the foil strip 4.

In Figs. 3 and 4 the box side walls have their upper edges turned over and inwardly as at 10, to form a supporting ledge upon which the foil strip 4 rests and to which it adheres by the adhesive 11. On top of this ledge thus formed there is applied the sealing medium 12 and then the cover 8 of the box is brought into position, slight pressure applied, and the seal is accomplished.

Referring to the folding box, there are two methods by which the foil is applied to a folding box. The first method is to assemble the box blank in the usual manner and then line the folded box either with a continuous sheet of foil after the adhesive has been supplied thereto, or by a plurality of strips that overlap one another and are sealed to one another. The second general method is to apply to the unfolded box blank a sheet of foil to those portions to which it is to permanently adhere on both the inside and outside of the blank, and to then fold the box and the surplus foil by allowing certain portions of the blank to be entirely free of and detached from the foil. The parts of the box blank are then hooked together in the usual manner and there will be found in the box a continuous sheet of foil which can be sealed into a gas-tight container.

Returning to the first general type of a box that is first folded and assembled into a container and then has the foil applied to it, we refer to Figs. 5, 6, 7, 8, 9, 10 and 11. The box blank shown in Fig. 5 consists of a front wall 13, a bottom 14, a rear wall 15, a top 16 and a top sealing flap 17.

The parts so mentioned are formed from a single sheet of stock and are hinged to one another along the score lines 18, 19, 20, and 21. The front wall 13 has hinged on either side thereof on the hinge line 22 end wall locking flaps 60 23, having locking slots 24. The bottom has hinged thereto end walls 25 hinged along the score lines 26. The back wall has hinged thereto along the score line 27 the locking flap 28 which has a hinged sealing flap 29 hinged thereto along 65 the score line 30. The assembled box is shown in Fig. 6.

This assembled box before the cover is closed has either a single strip of foil with its tacky adhesive backing applied on the interior of the box, or preferably a strip designated 31 is first applied to the bottom 14 and end walls 25. A transversely-arranged strip 32 is then applied to the inside of the front wall 13, the metal strip 31 on the bottom 14, the back 15, the inside of 75

the top 16, the inside of the sealing strip 17 and is then turned over and applied to the outside of the sealing strip 17. In the meantime, the strip 31 has been turned over on the outside of the sealing flaps 29. In Fig. 7 these turned-over strips of the foil have not been turned over, for purpose of illustration, upon the sealing strips 17 and 29. When this is accomplished, then the sealing medium is applied to the outside of the flap 17 as at 17-a, and to the outside of the sealing flaps 29, as at 29-a, and the box is thus closed and sealed.

Referring to Figs. 15 to 20, in this form in which the foil is first applied to the flat unfolded blank, the foil is adhesively applied to the inside of the front wall 13, the bottom 14, the end walls 25, the inside and outside of the sealing flaps 29, the back wall 15, the inside of the top 16, the inside and outside of the sealing flap 17. It overlaps but is not adhesively applied to the locking flaps 23 and 28. The box is then folded in the usual manner and the surplus portion of the sheet of foil is folded at the corners. Due to the fact that the adhesive material has the ability of rendering this structurally weak foil structurally strong, the foil will not tear even though bent and folded at the corners and even though not supported by the box blank. The outstanding characteristics of this medium used to coat this foil is the fact that it can convert a structurally weak metallic foil, that is so delicate as to necessitate extreme care in handling, into a material that has very marked structural strength.

Upon assembling the box, it is then loaded with its contents and by the application of the sealing medium to the outside of the flaps 17 and 29 the box is sealed.

Referring to the alternative form shown in the bag type in Figs. 12 to 14, the same procedure is followed. Either a foil bag with an outer coating of adhesive is applied to the paper bag on the inside thereof, or the paper bag is applied to the inside of the foil bag; or the bag blank has the foil applied thereto and is then assembled in the usual manner, using the adhesive for assembly purposes. The bag is designated 33. The foil liner or foil bag is designated 34, and the intermediate adhesive is designated 35. The mouth of the bag, when it is to be sealed, is folded over as in Fig. 13, has a sealing medium 36 applied thereto and then again folded over as in Fig. 14 and pressure is applied.

It will be understood that we desire to comprehend within our invention such modifications as may be necessary to adapt it to varying conditions and uses.

Having thus fully described our invention, what we claim as new and desire to secure by Letters Patent, is:

1. In a method of making a gas-tight container, forming a paper container, applying a metal foil to the walls of said container and interposing an adhesive between said foil and said container to render the foil structurally strong and permanently anchor it to the walls of the container, applying a sealing medium to a portion of the container and bringing a cover for the container into engagement therewith.

2. In a method of forming a gas-tight container, forming a paper container, adhesively applying a foil film that is structurally weak to the

interior of the bottom and the top of the container while separate from one another, whereby the structurally weak foil is made structurally strong and is permanently anchored to the paper container; applying a sealing medium to the engaging surface of one part of the container and bringing the other part of the container in closing engagement therewith whereby the container is sealed.

3. In a method of forming a gas-tight container, forming a paper box blank, including bottom and side areas assembling the box blank but not closing it, adhesively attaching a foil liner to said paper blank, applying a sealing medium to engaging portions of the blank when the container formed thereby is closed, and closing the container.

4. In a method of manufacturing a container, forming a box blank having a folded bottom, locking portions and a hinged top, said locking portions having sealing flaps for the bottom, and said top having a sealing flap on the top; applying an adhesive to a metal foil to structurally strengthen it and render it adhesive; applying said adhesive to the interior of said box blank while unfolded, consisting of applying it to all parts of the interior of the blank except the locking flaps and to both the interior and exterior of the sealing flaps, on the locking flaps and on the cover; and folding the box and utilizing the locking flaps to retain the box in folded position with an interior continuous lining of metal foil.

5. A new article of manufacture for use as a container comprising a top member and a bottom member formed of paper and adapted to form a container and a covering of structurally weak metal foil attached to the members by an adhesive, adherent to both metal and paper and a second adhesive adapted to seal engaging surfaces of the top and bottom members of the container and adhere thereto.

6. In combination, in a container, a box bottom having a marginal flange, a lining of metal foil adhesively and permanently connected to the interior of said box bottom and overlapping upon the top of said flange and an adhesive on the top of said flange and a cover adapted to engage with said adhesive to seal the box.

7. In combination, in a container, of a box bottom, an interior coating of adhesive extending over the top and along the outside margins of the box bottom, a layer of foil over the adhesive permanently attached to the box bottom and extending over the top of the bottom partially down the outside walls thereof, a layer of adhesive on the outside of the metal foil on the outside of the box walls; and a cover having a top and side walls adapted to engage with said outside adhesive to seal said box.

8. In a box, a blank comprising bottom, walls and top with a sealing flap and locking flaps a part of which have sealing flaps, a structurally weak metal foil film having a reinforcing adhesive backing so arranged that said film is applied to the interior of said blank with the exception of the locking flaps, which it overlaps, but is not attached to, said film being attached to both inside and outside of the sealing flaps on the locking flaps and the cover.
